DESIGN.

—o—
G. H. PHILLIPS.
HEATING STOVE.

No. 20,467.

Patented Jan. 6, 1891.

UNITED STATES PATENT OFFICE.

GEORGE HENRY PHILLIPS, OF GENEVA, NEW YORK.

DESIGN FOR A HEATING-STOVE.

SPECIFICATION forming part of Design No. 20,467, dated January 6, 1891.

Application filed December 13, 1890. Serial No. 374,629. Term of patent 7 years.

To all whom it may concern:

Be it known that I, GEORGE HENRY PHILLIPS, a citizen of the United States, residing at Geneva, in the county of Ontario and State of New York, have invented and produced a new and original Design for Stoves, of which the following is a specification, reference being had to the accompanying photograph, forming a part thereof.

10 The photograph illustrates a perspective of my design, it being deemed adequate to fully illustrate the same.

The leading feature of my design consists in a substantially rectangular base having 15 rounding corners, a plain top bar, and a lower ornamented bar formed with a compoundly-curved lower edge and downwardly-extending ribbed or fluted legs, a body portion within the plane of the base having ornamented curved 20 rounding corners disposed with their upper extremity in a plane within that of the lower extremity, a ribbed or fluted bar extending between two of said corners, a raised panel on either side of said bar, a raised panel 25 and bar on the side of the body portion of the stove, a top formed at its base with an upwardly-flaring ribbed fluted bar, a plain central bar, and a rounding curved ornamented top bar having a projecting ornament.

30 A represents the base of the stove, which is substantially rectangular in its general contour and is formed with a plain top bar B, an ornamented lower bar C, and downwardly-extending ribbed or fluted legs D.

35 E represents the body portion of the stove, which is also substantially rectangular in its general contour.

F F are the corners, of rounding cross-section, having an ornamented outer face, with

their upper extremity f disposed in a plane 40 within that of the lower extremity f'.

G represents a cross-bar which is between two of the corners F F, is preferably of round cross-section, and is ribbed or fluted transversely. On either side of the bar G are the 45 lower and upper raised panels H and I, which are essentially rectangular in their general contour, with their outer face suitably carved.

At the side of the stove-body is a raised panel J, disposed in a plane beyond that of 50 the corners F F, and beneath the panel is a projecting bar J'.

K represents the top of the stove, having at its base the lower bar L, which flares upwardly, is curved in cross-section, and is ribbed or 55 fluted transversely.

M represents the plain central bar of the top, and N the top curving bar having carving at its upper extremity and the upwardly-projecting ornament O.

This particular combination of curved, fluted, and carved surfaces in different planes presents a very pleasing, desirable, and highly ornamental appearance, which greatly increases the salability of the stove.

What I claim is—

The design for stoves, substantially as herein set forth.

In testimony whereof I have hereunto signed my name, in the presence of two attesting witnesses, at Geneva, in the county of Ontario, in the State of New York, this 6th day of December, 1890.

GEORGE HENRY PHILLIPS.

Witnesses:

WALTER A. CLARK,
EDGAR PARKER.
